UNITED STATES PATENT OFFICE.

GEORGE C. WHITTLES, OF LYNDHURST, NEW JERSEY, ASSIGNOR OF ONE-HALF TO
GUSTAVE SODERSTROM, OF NEWARK, NEW JERSEY.

LINE CONNECTER AND ADJUSTER.

Application filed November 21, 1921. Serial No. 516,584.

To all whom it may concern:

Be it known that I, GEORGE C. WHITTLES, a citizen of the United States, and a resident of Lyndhurst, in the county of Bergen and State of New Jersey, have invented new and useful Improvements in Line Connecters and Adjusters, of which the following is a specification.

One object of the invention is to provide a device embodying novel features of construction for easily and quickly connecting the ends of a clothesline or the like, connecting an end of a line to a support, and like purposes, and for quickly adjusting the length or tension of a line.

Further objects of the invention are to provide a device of the character described including a body portion having a longitudinal opening in one end thereof to receive an end of a line and a transverse opening through said body portion and meeting said longitudinal opening, and a clamping bar slidable transversely of said transverse opening adjacent the inner end of the longitudinal opening to clamp a line between itself and the inner edge of said longitudinal opening; to provide such a device having the clamping bar slidable in slots at opposite sides of said transverse opening substantially parallel to said longitudinal opening which slots enter said longitudinal opening so that lines of different sizes may be clamped between the said clamping bar and the inner edges of said opening; to provide a device of this character having the longitudinal opening at one end thereof and the other end formed to be connected to another end of a line or to a support, etc.; and to obtain other results and advantages as may be brought out by the following description.

Referring to the accompanying drawings, in which like numerals of reference indicate the same parts throughout the several views,

Figure 1 is a plan view of a line connector and adjuster embodying my invention;

Figure 2 is a side elevation thereof;

Figure 3 is a vertical longitudinal sectional view taken on the line 3—3 of Fig. 1;

Figure 4 is a transverse sectional view taken on the line 4—4 of Fig. 2;

Figure 5 is a fragmental longitudinal sectional view through a modified construction, and

Figure 6 is a transverse sectional view taken on the line 6—6 of Fig. 5.

In the embodiment of the invention shown on the drawings, the reference character 1 designates the body portion of the device which is provided at one end with a longitudinal opening 2 to receive an end of a line 3. The body portion 1 is also formed with an elongated transverse opening 4 which meets the opening 2, as clearly shown in Figures 3 and 4, thus forming a shoulder 5 at the inner end of said opening 2.

A clamping bar 5, preferably cylindrical, is slidably mounted in slots 6 in the sides of the body portion transversely of the opening 4, the slots 6 extending longitudinally of the body portion in or parallel to an axial plane of the opening 2 and entering into the inner end of said opening, as shown in Figures 1 and 3. The outer ends of the clamp bar 5 are provided with enlarged heads or finger pieces 7 which also prevent the bar from sliding out of the slots 6. The end of the body portion 1 opposite the opening 2 is provided with suitable means, such as the eye 8 for connection to an end of a line or to a support.

In the operation of the device, assuming that it is desired to use the same for connecting the ends of a pulley clothes line, one end of the line is permanently connected to the eye 8, and the other end after having been passed around the pulleys is passed through the opening 2 and upwardly over the clamping bar 5 and downwardly through the transverse slot 4, after which the clamping bar is moved toward the inner edge of the opening 2, as clearly shown in Figure 3. This movement may be accomplished either by the finger pieces 7 or by pulling upon the free end of line beneath the body portion. The line is thus securely clamped between the meeting point of said openings 2 and 4, or shoulder at the inner end of the opening 2 and the clamping bar, and the greater the tension on the line the tighter the same will be clamped in the device. When it is desired to disconnect the end of the line or adjust the tension or length thereof, it is merely necessary to push the clamping bar 5 away from the opening 2 or grasp the free end of the line and pull the same inwardly of the body portion. It will be noted that the intersecting relation of the slots 6 and the

opening 2 enables the clamping bar to closely approach the inner edges of the opening 2, whereby lines of different diameters may be clamped in the device.

5 A modified construction is shown in Figures 5 and 6 in which one side of the longitudinal opening 2 is cut away as at 9 to form in effect a groove, whereby the rope, line or the like may be inserted laterally in the 10 opening and thence threaded around the clamping bar, thus expediting the clamping of a line in the connector.

It will be understood that the device is 15 capable of use for connecting the ends of a pulley clothesline as described, for connecting the ends of two lines, ropes, cables or the like, for connecting the end of a line to a support, for bale and package ties, and like 20 purposes. While I have shown and described one embodiment of my invention, it will be understood that this is only for the 25 purpose of illustrating the principles thereof, and that modifications and changes can be made in the detail construction of the device without departing from the spirit or scope of the invention.

Having thus described the invention, what I claim is:

1. A device of the character described in-

cluding a body portion having an opening therethrough intermediate its ends, and a second opening meeting said first-mentioned opening intermediate the ends of the latter and at an angle thereto, and a clamping bar mounted in said body portion to move in a direction longitudinal of said second-mentioned opening, whereby a line or the like may be threaded through said openings and said bar clamp said line between itself and the meeting point of said openings. 30

2. A device of the character described including a body portion having an opening therethrough intermediate its ends and a second opening meeting said first-mentioned opening intermediate the ends of the latter and at an angle thereto, said body portion having slots arranged at opposite sides of and substantially parallel to said second-mentioned opening and entering the same, and a clamping bar mounted in said slots 45 to move longitudinally thereof, whereby a line or the like may be threaded through said openings and said bar clamp said line between itself and the meeting point of said openings, said slots permitting said bar to 50 closely approach said meeting point to clamp lines of different thicknesses. 55

GEORGE C. WHITTLIES.
